DESIGN FOR A TOWEL BAR POST OR SIMILAR ARTICLE

Harry Lang, New York, N. Y.

Application August 19, 1937, Serial No. 71,191

Term of patent 3½ years

To all whom it may concern:

Be it known that I, Harry Lang, a citizen of the United States and a resident of New York city, in the county of New York and State of New York, have invented a new, original, and ornamental Design for a Towel Bar Post or Similar Article, of which the following is the specification, reference being had to the accompanying drawing forming part thereof.

Figure 1 of the drawing is a top plan view of a towel bar post or similar article embodying my new design; and

Fig. 2 is a sectional view taken on line 2—2 of Fig. 1.

I claim:

The ornamental design for a towel bar post or similar article, as shown.

HARRY LANG.
